OF WASHINGTON.

PROCESS OF FORMING BRAKE-RINGS.

1,220,470.

Specification of Letters Patent. Patented Mar. 27, 1917.

Application filed December 14, 1915. Serial No. 67,108.

To all whom it may concern:

Be it known that we, JOHN F. SMITH and GUY H. WILLIAMS, citizens of the United States, and residents of Seattle, in the county of King and State of Washington, have invented certain new and useful Improvements in Processes of Forming Brake-Rings, of which the following is a full, true, and exact specification.

10 This invention relates to a process of manufacturing brake rings from steel T iron and has for its principal object to render the process of manufacture of brake rings cheaper and more rapid; to provide a superior brake ring as to quality of material. In the manufacture of brake rings, cast iron is generally used which possesses little tensile strength, deforms in casting, requires machine finishing, etc. By means of our process, a brake ring is formed in halves from a piece of T iron by cold cutting and forming. The accompanying drawings illustrate our brake ring process.

In the drawings, Figure 1 is a plan view of a complete brake ring. Fig. 2 is a half sectional elevation of Fig. 1. Fig. 3 is a detail showing the end of the T iron before bending.

Referring more particularly to the drawings, numeral 1 indicates the flange of a T iron and 2 the web. When completed the brake ring is in the form of a pair of similar semi-circular members of T iron with the flange outward. Friction wearing strips 3 are secured to the outside of the ring. Two of the adjacent ends of the semi-circular members are cut away on the web as at 4 and the end of the flange bent up at right angles against the end of the web. The other adjacent ends have semi-circles punched from them so that when the ends

are brought together, a complete hole as at 5 is formed. Both semi-circular members are cut away centrally on the web as at 6. In our process the length of material is first cut from stock, the end of the web cut away as at 4 and the flange end bent up. The opposite end is punched as at 5 and the web cut away as at 6. Holes 7 may also be stamped to receive springs 8.

Our brake rings may be formed by drop forging or by other hot processes, but I prefer cold cutting and forming as it increases the tensile resistance of the metal.

Claims:

1. The process of forming semi-circular brake rings from T iron, consisting in cutting away the web at one end of the piece of T iron, bending the flange of the T back at right angles and against the end of the web, 60 cold bending the piece of T iron into a semi-circular form with the web innermost, punching an open semi-circular notch in the end of the web opposite the said cut away end, and shearing away an edge portion of the 65 web midway between the two ends.

2. The process of forming semi-circular brake ring members, consisting in bending a piece of T iron in a semi-circle with the web innermost, cutting away a square portion of the web of the T iron at one end of the semi-circular member and bending the free end of the flange against the end of the web and on a diametrical line, punching an open semi-circular notch in the web of the 70 other end of the semi-circular member, and shearing a crescent shaped piece from the edge of the web midway of the ends of the 75 semi-circular member.

JOHN F. SMITH.
GUY H. WILLIAMS.
